Primary Examiner—Stella M Reid*Assistant Examiner*—Mark A Goodwin(74) *Attorney, Agent, or Firm*—Merchant & Gould PC(57) **CLAIM**

The ornamental design for a harvester bucket, as shown and described.

DESCRIPTION

FIG. 1 is a top right perspective view of a harvester bucket showing my new design;

FIG. 2 is a front elevational thereof;

FIG. 3 is a rear elevational view thereof;

FIG. 4 is a right side elevational view thereof, a left side elevational view not being shown as it is a mirror image thereof;

FIG. 5 is a top plan view thereof; and,

FIG. 6 is a bottom plan view thereof.

The portions shown in broken lines are for illustrative purposes only and form no part of the claimed design.
